COMPUTER COMMUNICATION TERMINAL

William K. David and William S. Sheppley, Jr., Poughkeepsie, N.Y., assignors to International Business Machines Corporation, New York, N.Y., a corporation of New York

Filed Nov. 10, 1960, Ser. No. 62,951

Term of patent 14 years

(Cl. D26—5)

FIG. 1

FIG. 2

FIG. 1 is a perspective view of the front, top and left hand side of a computer communication terminal showing our new design; and

FIG. 2 is a perspective view of the back, top and right hand side thereof.

The characteristic features of our design reside in the combination on the computer communication terminal disclosed of the cabinet portion having four separate narrow three-quarter length front and rear panels and two relatively wide, separate, full length side panels, disclosed upon a side vented recessed base and topped by a control cabinet having a sloping front panel and a vertical grille in the back; said control also having a recessed base which presents a horizontal break line, all as shown.

We claim:

The ornamental design for a computer communication terminal, substantially as shown and described.
